WEARING APPAREL HANGER

Earl S. Tupper, Smithfield, R. I.

Application December 18, 1956, Serial No. 44,241

Term of patent 14 years

(Cl. D80—8)

Fig. 1

I claim:

The ornamental design for a wearing apparel hanger, substantially as shown.
